UNITED STATES PATENT OFFICE

2,470,124

THREAD LETOFF FEEDING MECHANISM

George O. Young, Robesonia, Pa., assignor to
 Vanity Fair Mills, Inc., Reading, Pa., a corpora-
 tion of Pennsylvania

Application September 2, 1947, Serial No. 771,618

9 Claims. (Cl. 66—86)

1

My present invention particularly relates to mechanism for delivering thread, from warp beams, spools, bobbins, etc. of knitting machines, to the needles during the knitting process. In the production of fabrics made upon tricot or so-called fast warp machines, for example, the density of the fabric or tightness of the stitches is largely determined by the feeding, i. e., the portion of thread or yarn allotted to each knitting cycle. In order to prevent formation of so-called stop marks frequently formed in fabrics when the beam let-off is uneven or irregular it has been found desirable to provide some means to effect a continuous rotation of the beam in a manner to let-off exactly the amount of thread or yarn that is required by the needles.

While means have heretofore been devised for turning the beam or beams continuously during the knitting process, such means have been more or less complicated and expensive due to the changing speed of the beam as the thread is wound off.

My present invention has for its object to provide a beam etc. let-off or thread feeding mechanism of a simple and effective construction, inexpensive to produce and fully automatic in operation, serving to let-off thread at a continuous uniform linear speed regardless of the lessening diameter of the beam as the thread is taken from it.

In general, I provide for each beam a let-off device operated through a belt drive directly applied to the thread on the beam, the belt being kept under a constant tension throughout the operation of the machine and being driven at the same linear speed as that of the thread being let-off and that regardless of the diameter of the beam at any time of operation.

To the attainment of the aforesaid objects and ends invention also resides in the novel details of construction, combinations and arrangement of parts all of which will first be fully described and then be specifically pointed out in the appended claims, reference being had to the accompanying drawings in which:

Fig. 1 is a rear elevation of a portion of a knitting machine embodying my invention.

Fig. 2 is a side elevation of the same.

Fig. 3 is a detail schematic cross section showing the relative relations of the mechanism constituting the essence of the invention.

Fig. 4 is a detail rear elevation showing how the spreader passes the threads from beneath the belt past the sides of the same.

Fig. 5 is a diagrammatic view of a modification.

2

In the drawings in which like numerals of reference indicate like parts in all the figures, 1 represents one of the end frames of the knitting machine which are connected together by a bar 2 and are of the usual construction and per se do not constitute a part of my invention.

Angle iron bars 3 are secured to each side frame 1 and support an angle iron 4 which connects one bar 3 with the other and carries a pair of roller supporting plates 5 that are spaced apart to receive rollers 22 and 24 between them. One plate 5, at least, is provided with an extension 6 to which is secured an arm 7 that carries a stub shaft 8 on which a flanged pulley 9 is journalled.

15 A free flanged pulley 11 rides on pulley 9 and has a shaft 10 from which is freely suspended a pair of hanger bars 12 having a cross pin 13 to which is hooked a weight 14.

20 Mounted in bearing apertures in the plates 5 are the roller shafts 21 and 23 respectively. The shafts 21 and 23 are geared together by spur gears 15 and 16. The shaft 23 extends through a bearing 18 mounted on the angle iron bar 4 and carries a sprocket 17 over which an endless chain 51 passes.

25 The shaft 19 of the upper beam 20 is suitably mounted in suitable bearings in the end frames 1.

An endless belt 25 passes around the beam in direct contact with the thread or yarn, 29, 29^a of 30 the same. The belt also passes under roller 24, over roller 22, and under pulley 11 and over pulley 9. The weight 14 maintains a constant tension on the belt at all times.

35 A spreader plate 26 is mounted between the upper and lower flights of the belt 25 to the rear of the beam 20, as is also a spreader rod 27. All thread 29 except that beneath the belt is taken from the beam in the usual way. The thread 29^a from beneath the belt is taken from the place where the belt leaves the beam and passed under the bar 27 from which it passes through holes 26^a in the spreader plate 26 which holes are located to either side of the location of the belt and the threads 29^a thus by-pass the belt 45 before going under a guide bar 28 from which the thread goes to the usual tension rod (not shown) of the machine on the way to the thread guides and needles (also not shown).

50 When two beams per machine are used the thread feeding mechanism is duplicated for the other beam and the two mechanisms are hooked up together to operate simultaneously. This is accomplished as follows: Supporting bars 30 are secured to the bar 2 and carry a pair of roller

supporting plates 40 between which a second

pair of rollers 44, 45 are located, their shafts 33 and 42, respectively, being mounted in bearing holes in the plates 40. The plates 40 are connected by spacing rods 46. A bearing bracket 32^a is provided for the shafts 32 and 33.

A bracket 31 carries an idler shaft 34 on which is mounted an idler gear 37 which meshes with a driving gear 36 on a shaft 35 that is driven in any suitable way from the cam shaft (not shown) of the knitting machine. The idler gear 37 also meshes with a gear 38 on the shaft 32.

The counter shaft 32 also has a gear 39 that meshes with a gear 39^a on shaft 33. The shaft 33 is provided with a sprocket 47 in plane with sprocket 17 and with an idler sprocket 48 carried by an arm 49 that is secured at 50 to the end frame 1 shown in Figs. 1 and 2.

The rollers 44 and 45 are geared together by gears 41 and 43 on their respective shafts 33 and 42.

The chain 51 passes over sprockets 17, 47 and 48 and thereby the upper beam let-off is driven from the shaft 33 of the lower beam let-off as best shown in Fig. 2.

The shaft 52 of the lower beam 53 is mounted in suitable bearings in the frame 1 and a belt 54 passes over the beam, under the roller 44, over roller 45 under a free flanged pulley 60. The pulley 60 has hanger bars 61 suspended from its shaft 59 which bars 61 have a cross pin 62 from which a suitable weight 63 is suspended for the purpose of maintaining a constant tension on the belt 54. A spreader rod 55 and spreader plate 56 are suitably mounted between the flights of a belt 54 adjacent the beam, under which rod the threads 58 from under the belt pass to and through the spreader plate apertures and from whence the threads after by-passing the belt, go under a guide bar 57 before passing to the tension rod, etc. (not shown). The other threads 58 pass off the beam directly.

In the modified form, Fig. 5, the rollers 122 and 124 are located at the front of the machine, the spreader plate 126 is located between the upper and lower flights of the belt 125 in front of the beam 120. Tension is maintained on the belt by a pulley 121 to which a weighted cable 64 is attached, the cable 64 passing over an idler pulley 65 suitably supported above the beam. The bypassed threads 129 from the spreader plate 126 pass under a tension rod 128 in front of the beam which in this embodiment turns in a direction opposite to that of the beam 20 in the first embodiment.

Other modifications will be apparent to those skilled in the art.

From the foregoing it will be seen that as the thread diameters of the beams decrease the belts will remain in contact with the same at a constant tension and so the linear speed of the threads from beams to the needles will remain constant.

The rollers 22, 24, 44, 45 are preferably made of rubber or rubber faced rollers may be used with belts of suitable non-slip material.

From the foregoing description taken in connection with the accompanying drawings it is thought the construction, operation and advantages of my invention will be clear to those skilled in the art.

What I claim is:

1. In a thread let-off mechanism, in combination with a beam, an endless driving belt taking over the thread on the beam, means for driving said belt at a fixed linear speed, means for main-

taining tension on said belt by virtue of all of which the thread leaves the beam at the same constant linear speed as that of the belt, and means to by-pass the belt with the thread that is unrolled from beneath the belt.

2. A thread let-off mechanism according to claim 1 wherein the by-passing means comprises a spreader plate engaging the thread to be bypassed.

3. A thread let-off mechanism according to claim 1 wherein the by-passing means comprises a spreader plate engaging the thread to be bypassed and a spreader rod engaged by the thread to be by-passed before it passes to the spreader plate.

4. In a knitting machine employing at least two beams, the improvement which comprises: a let-off mechanism for each beam, each said let-off mechanism including an endless beam-driving belt running on the thread of the beam, means to drive said belt at a constant linear speed, means to maintain a constant tension on said belt, and means for receiving the thread from beneath the belt and spreading it laterally to by-pass the belt.

20 5. The improvement of claim 4 wherein the belt driving means for the two beams includes a driving connection between the two said means, and a primary drive to one of said belt driving means.

6. In a knitting machine wherein is provided a frame, a thread beam journaled in bearings in said frame, and a driving shaft, the improvement which includes an endless driving belt passed over the thread on the beam, a pair of belt driving rollers engaging said belt and suitably mounted on said frame, means to drive said rollers from said driving shaft at a constant speed, means for taking the thread of the beam which is beneath the belt and by-passing the belt with said thread and means to maintain a constant tension on said belt.

7. In a thread let-off mechanism for beams, a beam supporting frame, bearing plates mounted on said frame, a pair of belt-driving rollers having shafts journaled in said plates, a fixedly located belt pulley carried by said frame, a weighted free belt pulley cooperating with said fixedly located belt pulley, an endless belt engaging said pulley and rollers and passing around the beam on a section of the threads thereof, means to cause said rollers to drive the belt at a predetermined linear speed and thereby let-off thread at the same linear speed as that of the belt, and means for deflecting the thread beneath the belt as it is let-off to clear the edges of the belt.

45 8. A mechanism according to claim 7 wherein said deflecting means includes an apertured spreader plate through whose apertures the threads released from beneath the belt are passed.

50 9. A mechanism according to claim 7 wherein the belt driving rollers are intergeared and the driving power is applied to one of said rollers.
